UNITED STATES PATENT OFFICE

WELLS S. FLEMING, OF PORTLAND, OREGON

CONVERTIBLE DRAIN FITTING

Application filed July 31, 1928. Serial No. 296,451.

The object of this invention is to provide a convertible drain suitable for use as a floor drain, especially suitable for shower baths; also suitable for use as a roof drain. Furthermore to provide a drain fitting of simple, practical, and relatively inexpensive construction adapted to be set in floors of plastic composition of various thicknesses; and in connection with which a sheet of water proofing material may be used to provide a watertight condition; and to this end to use devices that are accessible after the floor is laid, so that repairs may be made without injury to the floor.

15 A further object of my invention is to provide a floor drain in connection with which a testing sheet or gasket may be employed for temporarily closing the opening leading to the connected drain pipes of the building; so 20 that the plumbing may be tested under pressure if required by the building code of the locality.

25 A still further object of my invention is to provide a drain fitting which is readily convertible from the usual floor drain type having a grille plate opening laid flush in the floor, to a drain having a dome-plate fixedly secured at the floor level and extending upwardly with slotted openings of a type suitable for roof drains, or in floors of factories.

30 Other features and advantages of my invention, and the details of construction and arrangement of my invention are hereinafter described with reference to the accompanying drawings which illustrate the preferred form of my invention.

In said drawings:

35 Fig. 1 shows a vertical section of a floor with a drain embodying my invention set therein;

40 Fig. 2 shows a side elevation, broken away in part, of the several parts comprising my invention as shown in Fig. 1, with the parts vertically lifted and separated from each other, but positioned for assembly;

45 Fig. 3 shows a plan view of a testing plate or gasket which may be employed with my invention;

50 Fig. 4 shows a vertical section of a modified type of my invention; as here shown a dome

drain plate is employed instead of a grille plate;

55 Fig. 5 is a side elevation of the said modified type of my invention shown in Fig. 4 with parts broken away with the parts vertically separated from each other but arranged for assembly;

60 Fig. 6 is a plan view partly broken away of the type of my invention shown by Figs. 1, 2 and 3 inclusive; and

Fig. 7 is a similar plan view of my invention modified as shown by Figs. 4 and 5.

65 Referring first to Figs. 1, 2, and 3, my invention comprises a tubular body 1, of which the bore 2 is provided with an interior thread 3 with which the end of a drain pipe, not shown, may be connected. The upper end of the body is provided with an upwardly inclined circumferential lateral flange 5, the upper surface of which is formed with a conical depression 6, and terminates at its outer periphery in a horizontally disposed portion 7. Radially arranged internally threaded 70 bolt recesses 8 are provided in the flange concentric with its bore.

75 A clamping plate 10 is provided, adapted to be seated on the flange 5, in the said conical depression 6, and has a central opening 12 registering with the bore 2 of the body 1. Bosses 13 are formed on the clamping plate 10 in which holes 15 are provided registering with the bolt recesses 8, and bolts 17 are provided, adapted to be inserted through the holes 15 and threaded into the bolt recesses 8, by which the clamping plate is secured on the body 1.

80 The outer margin of the plate 10 has an integral circumferential wall 18 forming a circular chamber 20. The wall 18 converges slightly towards the top and screw threads 21 85 are provided on the interior surface of the said wall 18 and spaced, radial openings 22 are provided adjacent its base opening into the chamber 20.

90 A cylindrical drain section 23 having a bore 26 is provided threaded as at 25, on its exterior surface and adapted to be threaded into the chamber 20. The upper end of said drain section 23 is off-set as at 27, forming an interior shoulder 28 on which a strainer 100

plate 30 is adapted to be seated, formed with slotted openings 31 to permit drainage into the body 1.

In installing my improved convertible drain fitting in a building, the body 1 is set upon the sub-floor 35, see Fig. 1, and a water proof sheet 36 of sheet lead or other suitable water proofing material, provided with a circular hole is fitted symmetrically over the conical depression 6 of the flange 5 of the body 1.

A circular testing gasket 37 of thin sheet lead or other easily rupturable material is then placed over the body 1, provided with circumferential slots 38 adapted to register with the bolt recesses 8. If other material, such as roofing paper is used, the slots 38 need not be provided, the bolts 17 merely being forced through it.

The clamping plate 10 is then laid over the flange 5 of the body and screwed down firmly thereon by the bolts 17 to secure the water proofing material 36, and the testing gasket 37 in water tight relation. The drain section 23 is then mounted on the clamping plate 10.

The floor 40 of plastic composition or other suitable material is then laid. The outer surface of the wall 18 is preferably wrapped with a strip of fabric, not shown, to cover the openings 22, and thus to protect these from plastic material getting therein, but offering no barrier to the percolation of water therethrough. The grille plate 31 may then be set in position to complete the installation of the drain. The testing-gasket 37 also serves the purpose of preventing the entrance of dirt, concrete, or other clogging waste material into the drain pipes during the construction period of the building, and further serves the desirable purpose of permitting the drain pipe to be tested for leaks, as required in building codes of most cities. Upon such test being completed, and the plumbing being put to use, the central portion of the testing gasket may be removed by cutting it away around the interior of the bore 2.

Referring now to Figs. 4, 5 and 7, illustrating a modified form of my present invention: the body 1 is constructed similarly to that part of my drain fitting above described. A clamping plate 41 is formed similarly to the equivalent clamping plate 10, excepting that the vertically disposed wall 18 of the latter is omitted. A drain section 42 is formed with a lateral circumferential flange 43, which is adapted to be seated on the clamping plate 41, the flange 43 being provided with bolt holes 45 to receive the bolts 17.

Said drain section 42 extends upwardly in a bee-hive dome 46 formed with slots 47 in its side wall for drainage, and the perpendicular walls of the dome 46 extend below the flange 43, as at 48 and are provided with pro-

longations of the slots 47. This modified form of my invention is particularly suitable for roof drains, or for floor drains in factories, packing houses, and the like where considerable quantities of refuse material may be accumulated about the drains.

I claim:

1. A drain fitting, consisting of a tubular body formed with a lateral flange the upper face of which has a conical depression, an annular clamping plate having a bottom conforming with said depression and adapted to be secured on said flange with a sheet of water proofing material therebetween, said clamping plate having an integral wall extending upwardly, formed with drain openings at its base, and an inward projection at the top overhanging its interior chamber, said projection provided with interior screw-threads, a drain section having an external screw-thread adjustable in said wall, and a strainer plate seated in the upper end of said drain section having an annular skirt extending downwardly within the wall of said drain section.

2. A drain fitting, consisting in a tubular body formed with a lateral flange, the upper face of which has a conical depression, an annular clamping plate having a bottom conforming with said depression and adapted to be secured on said flange, said plate having substantially vertical wall about its outer perimeter enclosing an interior chamber, formed with slotted openings about its base and provided with internal screw-threads at its upper end, a threaded drain section supported on said clamping plate.
